UNITED STATES PATENT OFFICE

102,261

DESIGN FOR A TEXTILE FABRIC

Marcel Christen, New York, N. Y., assignor to Mitchell & Weber, Inc., New York, N. Y.

Application November 7, 1936, Serial No. 65,760

Term of patent 3½ years

To all whom it may concern:

Be it known that I, Marcel Christen, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric, substantially as shown.

MARCEL CHRISTEN.
